UNITED STATES PATENT OFFICE

ARTHUR R. SCHWARZKOPF AND RICHARD R. WAGNER, OF CHICAGO, ILLINOIS, AS
SIGNORS TO THEO. A. KOCHS COMPANY, OF CHICAGO, ILLINOIS, A CORPORATION OF
ILLINOIS

BARBER'S POLE

Application filed November 24, 1928. Serial No. 321,608.

This invention relates to barbers' poles, and more particularly to the illuminated type of barber's pole. One of the principal objects of the invention is to provide improved means for safeguarding the electric lamps, fixtures and wires against rain, snow and sleet. Another object is to provide a novel assembly of parts between the outer structure of the barber's pole and the illuminating means.

10 With these and other objects and advantages in view, this invention consists in an illuminated barber's pole having means for affording air circulation through the interior thereof and for draining out water and other 15 liquid, thereby preventing the entrance of water to the interior of the structure and short circuiting the electric conductors.

It further consists in certain novel connections between a transparent or translucent 20 shade or globe and the supporting member therefor. It further consists in the several novel features of construction, arrangement and combination of parts hereinafter fully set forth and claimed.

25 The invention is clearly illustrated in the drawing accompanying this specification in which—

Figure 1 is a side elevation, partly in central vertical section, of a barber's pole embodying a simple form of the present invention;

Fig. 2 is a horizontal section taken on the line 2—2 of Fig. 1;

Fig. 3 is an enlarged detail vertical fragmental cross section taken on the line 3 of Fig. 2; and

Fig. 4 is an enlarged detail vertical fragmental cross section taken on the line 4 of Fig. 2.

40 Referring to said drawing, the reference character 5 designates an upright bracket which is provided with means whereby it may be fastened to the side of a building or other structure. From said bracket projects 45 horizontal arms 6 and 7 to which are secured flanges or rings 8 and 9. Extending between the flanges 8 and 9 is a hollow translucent cylindrical body 10 which may be striped in accordance with the conventional method of 50 striping barbers' poles, and to the lower end

of the flange 9 is secured an ornamental cap 11 designed to give a finished appearance to the lower end of the device. Suitable packing 12 may be interposed between the translucent cylindrical body 10 and the flanges 8 and 9 so as to make a tight joint between those parts.

Resting upon the upper flange 8 is a collar 13 which is formed with a down turned rim or flange 14 that surrounds and overhangs the upper edge of the flange 8, and upon the internal face of the collar 13 are formed inwardly extending lugs 15 which rest on the upper edge of the flange 8. The collar 13 converges towards its upper end, as shown in Fig. 1, and below the upper edge thereof it is formed with an annular inwardly extending horizontal flange or wall 16 from which extends a vertical annular cylindrical flange or wall 17. The annular flange 17 and the end portion 18 of the wall of the collar 13 define between them an annular channel or groove 13^a in which the rim 19 of a shade or globe 20 is received. Drain apertures 21 are provided in the wall portion 18 of the collar through which water and other liquids may drain out of the channel or groove 13^a.

The shade or globe 20 may be of any suitable type and its rim 19 is held in spaced relation to the walls 17 and 18 and is supported above the horizontal wall 16 by lugs 22 which are formed upon the upper face of said horizontal wall 16. By supporting the lower edge of the shade or globe above the upper surface of the wall 16, and by spacing it from the walls 17 and 18, a free passage is afforded between the interior and exterior of the device, whereby outside air may circulate through the same. By reason of the drainage openings 21 snow, sleet or rain which may collect in the groove or channel 13^a is free to drain out therefrom instead of entering the shade or interior parts of the structure.

On the inner face of the wall portion 18 are formed lugs 23 which project into the annular channel or groove and form means for spacing the rim of the shade or globe away from the wall portion 18. At one side of the wall portion 18 is a set screw 24 which extends

through the wall 18 and bears against the side of the rim 19, whereby the latter may be securely held in spaced relation to the wall 18 between the lugs 23 and set screw 24. 5 The set screw 24 extends through an unthreaded hole in the wall 18 and a U-shaped clip 25 is provided for connecting the set screw to the collar, said clip having apertures through which the set screw 24 extends, 10 one of said apertures being threaded for engagement with the threads of the set screw 24. The collar 13 may be made of ceramic-ware and the metal clip 25 is provided to afford the threaded connection with the set 15 screw 24.

For illuminating the shade or globe 20 and the cylindrical body 10, incandescent electric light bulbs 26 and 27 are provided which are held in electric lamp sockets 28 and 29 supported upon the ends of pipes 30 and 30^a, 20 which form conduits through which the electric conductors may run to the sockets. The pipes are threadedly secured in a hickey or fixture stud 31 secured to and supported by 25 a hanger bar 32. The pipe 30 extends up through an opening in the collar defined by the flange 17, and the pipe 30^a extends down into the body 10. The hanger bar extends across the top of the flange 8 and its ends are 30 secured thereto by screws 33. Openings 34 are provided in the flange 8 for the admission of the electric conductor cords to the interior of the device.

As has been explained, the collar 13 rests 35 upon the flange 8. It is secured thereto by two threaded rods 35 which are fastened to the hanger bar 32 and extend through a ring 36 which rests upon the upper edge of the wall or flange 17. Upon the threaded ends 40 of the rods 35 are nuts 37 which bear against the upper face of the ring 36.

From the above it is to be observed that any water which enters the channel or groove in the top of the collar 13 is free to drain out 45 through the drain openings 21 and that the construction and arrangement of the collar 13 prevents water, snow, sleet, and other moisture, from entering the interior of the structure. Furthermore, by reason of the fact that 50 the rim portion of the globe is supported above the horizontal wall or flange 16 and is spaced away from the annular walls 17 and 18 of the collar, a free passage is afforded for the entrance of outside air to the interior of 55 the structure. Furthermore, the hanger bar 32 provides means for supporting the electric light fixture as well as for attaching the collar 13 to the flange 8. The structural members of the device may be enameled and otherwise ornamented as is most desirable. 60

We claim:

1. In a barber's pole, a shade supporting collar having bottom and inner and outer annular walls defining a central opening at its 65 upper end and an annular channel surround-

ing said opening, there being spaced shade supporting lugs on the upper face of the bottom wall of said channel, and there being inwardly projecting lugs on the inner face of the outer wall of said channel, and a set screw 70 threadedly connected with said outer wall of the channel and co-operating with the lugs on the inner face of said wall to secure a shade in place on said collar with its lower edge portion spaced from the several walls of the 75 channel.

2. In a barber's pole, a shade supporting collar formed with an outwardly and downwardly flaring skirt portion provided with an annular channel at its upper end adapted to receive the rim portion of a shade, the upper end of the skirt portion forming the outer wall of the channel and there being a drain opening through said outer wall of said channel. 80

In witness whereof, we have hereunto set our hands this 21st day of November, 1928.

ARTHUR R. SCHWARZKOPF.
RICHARD R. WAGNER.
